B. Douglas,

Heating Stove.

NO.

Patented June 30, 1830.

June 30, 1836

Sarah Douglass of Albany a. m. b. s. v.

Letters Patent.

The schedule referred to in these Letters Patent and making part of the same, containing a description in the words of the said Sarah Douglass herself, of his improvement in the booking stove.

Be it known that I Sarah Douglass of the city and County of Albany and State of New York, have invented a new and useful booking stove, which is described as follows, reference being had to the annexed drawings of the same, making part of this specification. A circular cast iron plate A, of about 30 or 33 inches in diameter or of any convenient dimensions, is placed horizontally on legs 3 or 4 inches high, near the front this plate is cut out in a circle eight inches in diameter to admit a gentle B, over which is set an upright cast iron cylinder or fire box, about 11 inches in height, on the top of this box is placed another circular plate D, of the same dimensions as the one just described, in which a circular aperture is left to admit the upper end of the fire box top pipe for the fire and smoke to pass. The under edge of the upper plate, and the upper edge of the under plate, are grooved to admit a piece of sheet iron E of the same width of the height of the cylinder or fire box, and which is bent or shaped into a circular form to fit into the grooves in the plates, which, with the door, encloses the fire box, and forms a large heat retained, or oven. Two side doors are into the upper plate, passing through the lower plate, and are secured with bolts, binding the holes together, above the upper plate are two connected collars F, for the passage of the fire and smoke and for boiler, under which the fire pipe passes the centre of the door, from front to back, where it enters the pipe. These collars are formed by a horizontal cast iron B, grooved in the under side, to which several hands are made in the plate. Into these grooves side pieces

6. are placed, of sufficient height for the boiler which are secured by screwing down the horizontal rim to the plate, thus uniting and holding fast the sides. On each side of these collars are openings 7, for boilers which are heated from the hot air in the oven. The receiver 8, for the ashes is placed under the cylinder projectors and is formed by a circular plate 9, of about sixteen inches in diameter, grooved near the upper edge, to receive a band with which there is made a groove in the under side of the lower large plate, a strip of sheet iron 10, is bent into these grooves of six inches in width, and is wedged or confined by screwing together the two plates. Within this receiver, or ash box, is an instrument for cleaning the gate from ashes which may be called a shaker. It is formed by a shaft 11, distant two or three inches from the gate and confined in boxes, to the plate above. The front end projects through the side of the box, sufficiently far to receive a moveable cumb or straight handle 12, of about one foot in length for operating it. At right angles with this shaft two or bars 13, project from it to the centre of the gate, to which are attached perpendicular flat, iron rods, 14, or poles, which are forced up and down through the gate by vibrating the shaft to the right & left by the hand. Notary stands similar to the one represented at 15, are placed in the oven for the convenience of supporting and turning articles of cooking towards the fire box, or in any other position required. They are formed by a bottom iron, eight or nine inches in diameter from which three pieces of iron obliquely upward to a circular centre piece 16, on which is placed a central stone 17, which has a fire on the top that enters the centre; a plate 18, pierced with a number of holes having the same diameter as the bottom iron and is supported by braces against the stem on the under side and can be easily turned around on the pivot horizontally. — The fuel designed to be used principally in this oven is the charcoal coke, but wood may also be used by altering the shape of the fire box from a circle to that of a rectangular figure.

figures for the more convenient introduction of the sticks of wood; there being made a door in front for that purpose.

What I claim as my invention and which I desire to secure by Letters Patent, consist in the combination and arrangement of the several parts of the stove in the manner before described. But I particularly claim the peculiar arrangement of the oven by which boilers are set in or through the top plate by which they are thus heated from the hot air therein; the mode of constructing the ovens and the manner of conducting the fire and smoke from the front to the rear over the ovens; the manner of constituting the body of the stove and the ashbox; the method of constructing the shakers or vibrating poker for cleaning the ovens; and the rotary or moveable stand for the convenience of the oven.

In testimony whereof I have hereunto set my hand in this twenty third day of May, A.D. one thousand one hundred and thirty six.
